(57) **CLAIM**

The ornamental design for a display screen with graphical user interface, as shown and described.

DESCRIPTION

The patent file contains at least one drawing executed in color. Copies of this patent or patent application with color drawing(s) will be provided by the Office upon request and payment of the necessary fee.

FIG. 1 is a first image for the new design of a sequence for a display screen with animated graphical user interface;

FIG. 2 is the second image thereof;

FIG. 3 is the third image thereof;

FIG. 4 is the fourth image thereof;

FIG. 5 is the fifth image thereof; and,

FIG. 6 is the sixth image thereof.

The outermost broken line shown in the figures represent the unclaimed boundary of the display screen. The remainder of the broken lines illustrate unclaimed portions of the display screen and animated graphical user interface.
